(57) **CLAIM**

The ornamental design for a tread portion of an automobile
tire, as shown and described.

DESCRIPTION

FIG. 1 is a perspective view of a tread portion of an automobile tire according to our design;

FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a fragmentary enlarged front view showing the
details of the tread portion thereof;

FIG. 8 is a section view taken along line 8-8 in FIG. 7; and,

FIG. 9 is a section view taken along line 9-9 in FIG. 7.

In the drawings, the broken lines defining the sidewall, inner
bead and the peripheral boundary between the claimed tire
tread and the unclaimed sidewall depict environmental sub-

ject matter that forms no part of the claimed design.
